(57) **CLAIM**

The ornamental design for a lens holder of automobile surveillance camera, as shown and described.

DESCRIPTION

FIG. 1 is a front, right and top perspective view of a lens holder of automobile surveillance camera showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, left and bottom perspective view thereof;

FIG. 9 is a cross-sectional view thereof along line 9-9 in FIG. 2; and,

FIG. 10 is a cross-sectional view of FIG. 9 shown in use. The broken lines rendered in FIG. 10 illustrate the environment of the claimed design and form no part thereof.

1 Claim, 10 Drawing Sheets
